CHIMNEY CONSTRUCTION

Robert J. Simpson, San Clemente, Calif.

Application December 10, 1956, Serial No. 627,206

1 Claim. (Cl. 72—94)

This invention relates to chimneys and has particular reference to a smoke chamber construction which finds particular utility in connection with the chimneys of fireplaces such as are used for residential heating.

In the construction of chimneys, and particularly in the construction of those chimneys used for residential fireplaces, it is common practice to provide a smoke chamber between the fire box and the flue which interconnects the fireplace throat with the flue proper. Such smoke chambers are of tapered cross-section, forming a transition between the relatively large cross-section of the chimney just above the fireplace throat to the much smaller cross-section of the flue. When, as is often the case, such chimneys are constructed of discrete elements or building blocks such as bricks or stones, the building blocks must be so placed and laid as to provide the required inward and upward taper of the sides of the smoke chamber. This must be done in such a manner as to provide an adequate support for the flue lining which is rested on the upper edge of the walls of the smoke chamber. This construction is ordinarily effected by corbelling, an exacting and time-consuming operation requiring great skill and extreme care, as a consequence of which the construction of smoke chambers represents a relatively costly item in the construction of the fireplace and associated chimney.

In order that the fireplace and chimney may operate properly, the inner surfaces of the smoke chamber must be smooth and free of the projections and discontinuities characteristic of corbels in order to reduce to a minimum the frictional resistance to the passage of the smoke and flue gases. Consequently, it is a common practice to apply mortar or a similar plaster to the inner surfaces to provide the desired smooth and continuous surface. This practice entails certain disadvantages since, unless carefully and expertly done, the plaster may in time be loosened by the expansion and contraction of the structure which results from the wide variations in operating temperature.

It is, therefore, an object of this invention to provide a chimney construction which overcomes the abovementioned disadvantages by providing for simple and rapid construction of a smoke chamber and which does not require highly skilled labor for its erection.

It is another object of this invention to provide a method of constructing smoke chambers in block chimneys which consists in placing a pre-formed support at the smoke chamber location and setting the blocks against said support, whereby the same are properly positioned and supported during the placing and setting thereof.

It is also an object of this invention to provide a method of the character set forth in the preceding paragraph in which said support is perforated and mortar is used to secure said blocks to each other and to said support, and wherein mortar extruded through the perforations is troweled to a smooth finish to provide an inner plastered layer, whereby said support serves also

2

to reinforce said mortar and to secure said plaster layer against loosening and falling.

It is an additional object of this invention to provide a pre-formed support for the walls of smoke chambers in chimney constructions comprising upper and lower frame members having dimensions conforming to the top and bottom cross-sections of the smoke chamber, said frames being spaced vertically by supporting members secured to and interconnecting said frames, and a sheet of perforated material surrounding said frames and extending therebetween.

It is an additional object of this invention to provide a pre-formed support of the character described in the preceding paragraph in which said frames and supporting members are formed of metal rods or bars and in which said perforated material comprises a metal screen, such as metal lath.

It is a still further object of this invention to provide a smoke chamber for chimneys comprising a rigid supporting and reinforcing structure including a tapered, a tubular or open-ended box having metal mesh walls secured to a metal framework, said box being open at the top and bottom, a plastered layer on the inner surface of said walls formed of mortar keyed through the openings in said metal mesh, and an outer layer of building blocks such as bricks or stones set against said walls and secured thereto and to each other by said mortar.

Other objects and advantages of this invention will be apparent from a consideration of the following specification, read in connection with the accompanying drawings, wherein

Figure 1 is an elevational view of a residential type fireplace showing the fire box opening and indicating by dotted lines the smoke chamber and flue;

Figure 2 is an enlarged fragmentary sectional view taken substantially along the lines 2—2 of Figures 1 and 3 and illustrating the construction of the upper part of the fire box, the smoke chamber, and the lower part of the flue;

Figure 3 is an enlarged fragmentary sectional view similar to Figure 2 but taken at right angles thereto as indicated by the lines 3—3 of Figure 2; and

Figure 4 is a perspective view illustrating a preferred form of construction of a pre-formed support used in the practice of the method of this invention and incorporated as a part of the smoke chamber construction.

Referring to the drawings wherein a preferred embodiment of the invention is shown, Figure 1 illustrates a residential fireplace of the flush type, the fireplace comprising a fireplace front indicated generally at 10 formed of discrete building blocks such as bricks, as shown in Figure 1. The structure 10 defines a fireplace opening 11 communicating with a fire box 12. The chimney proper indicated by the dotted lines 13 is set back behind the building wall which is represented at 9.

As is best shown in Figures 2 and 3, the structure 10 is formed of brick laid in the conventional manner. The chimney 13 is defined by a rear wall 14 and a front wall 15, the latter being set back as indicated at 16 to provide a suitable support for the building wall studs 17 and plaster facing 18. The sides of the chimney are defined by inner walls 19 and outer walls 20. The inner walls 19 together with the front and rear walls 14 and 15 define the flue proper, the flue being lined with an appropriate flue liner 21 which is supported and rested upon a shelf or projection 22 formed by courses of bricks 23 surmounting the smoke chamber indicated generally at 24. As will be seen in Figures 2 and 3, the smoke chamber 24 has an uppermost cross-sectional area conforming to the cross-sectional area of the flue lining 21 and a lower cross-sectional area conforming to the cross-

section of that part of the smoke chamber which lies above the smoke shelf 25, the latter being formed by the forwardly and upwardly curving back 26 of the fire box 12.

The back 26 extends to a point spaced a relatively short distance from a sloping front wall 27 to define a narrow throat indicated generally at 28, the throat conventionally being fitted with a damper construction such as is represented at 29.

The present invention is concerned with the construction of the smoke chamber 24. It will be appreciated that the construction of that part of the chimney lying above the flue liner support 22, 23 proceeds relatively rapidly and the bricks forming the same may be laid by relatively unskilled masons. However, as may be seen from Figure 3, the smoke chamber 24 requires the construction of at least two corbels formed by inwardly staggered courses of brick such as are shown at 30 in Figure 3. The construction of a corbel requires a high degree of masonry skill and is work which must necessarily proceed slowly if a good, sound, strong structure is to result.

According to the present invention, the construction is built up to the bottom of the smoke chamber, that is to the brick courses indicated by reference character 31 in Figures 2 and 3, in the conventional fashion. At this point a novel smoke chamber preformed support 32 is used to greatly facilitate the construction by providing a support for the corbelled courses 30 and at the same time adequately support and hold an inner plastered layer 33 which provides the desired smooth and unbroken interior surface. The construction of the smoke chamber support is illustrated in detail in Figure 4.

As may be seen in Figure 4, the smoke chamber support 32 comprises an upper frame 34 and a lower frame 35 held in spaced parallel relation by interconnecting supporting members 36 extended from the corners of the lower frame 35 to corresponding corners of the upper frame 34. The frames 34 and 35 are shaped to conform to the cross-sectional shape of the flue lining 21 and the lower portion of the smoke chamber, as defined by the brick courses 31. These frames are preferably constructed of iron rods suitably bent and welded, but may be made of angle iron or other structural members, similar material preferably being used for the interconnecting supports 36, the latter being appropriately secured to the corners of the frames as shown as by welding or similar means.

The box-like support 32 is of course open at the top and bottom; the sides, however, are covered with a metal mesh or perforated material such as metal lath, as indicated at 37, the material covering the four sides of the box-like form and being appropriately secured to the previously-described structure, as by spot-welding, wire ties, or other equivalent means.

In utilizing the support 32 the same is rested on the upper surface of the brick course 31 as shown in Figures 2 and 3 and the perforated walls 37 are generously coated with mortar. The individual courses 30 forming the corbel are then laid by merely placing them in contact with the walls 37 of the support 32, mortar being suitably applied to the bricks to bond the same to each other as in conventional brick-laying practice. Since it is a very simple operation merely to slide each of the bricks of the courses 30 inwardly into contact with the perforated walls 37, the corbel is formed very rapidly and in such a way as not to require the exercise of any great degree of skill. The mortar which is applied to the bricks in the usual fashion adheres, of course, to the mortar coating previously applied to the perforated walls 37 so as to provide an integral bond between adjacent bricks and between those bricks and the smoke chamber wall-supporting member. The operation of sliding the bricks inwardly into contact with the perforated walls 37 forces

a substantial amount of the mortar through the perforations to key the mortar to the structure. This inwardly protruding mortar is then troweled to a smooth finish to provide the inner plaster coating 33.

It will be seen that the lower frame member 35 is rested upon the upper surface of the brick course 31 and that the upper brick course 23 is correspondingly rested upon the upper frame member 34. The corbel formed by the courses 30 serve to provide the necessary structure for supporting the upper course 23 from the structure which lies below the course 31. From the upper end of the smoke chamber 24, as defined by the course 23, the flue construction proceeds in the conventional fashion.

It will be seen that when the structure is completed, there is provided a smoke chamber which is characterized by a rigid supporting and reinforcing structure carrying on its inner surface a plastered layer formed of mortar keyed through the openings in the metal mesh, and an outer layer formed of bricks or other building blocks which are set against the walls of the support and secured thereto and to each other by the mortar used in the construction. The support thus not only provides for ready and rapid construction of the smoke chamber by relatively unskilled masons, but also provides for a structural reinforcement of the finished structure. What is even more important, the inner plastered layer is mechanically secured to the rest of the structure by reason of the keys which are formed through the openings in the metal lath, thus avoiding all possibility of the plastered layer 33 coming loose and falling as sometimes happens because of the extreme changes in temperature to which the structure is subjected during normal operation.

While the preferred embodiment of the invention has been illustrated and described herein, the invention is not to be limited to the details shown and described, except as defined in the appended claim.

I claim:

40 A chimney smoke chamber comprising: a rigid framework comprising spaced parallel upper and lower generally rectangular frame members having dimensions corresponding respectively to the top and bottom cross-sections of the smoke chamber and having a plurality of supporting members each extending inwardly and upwardly from said lower frame member to said upper frame member at the corners thereof and rigidly secured to said frame members, said frame members and said supporting members comprising metal rods; a side wall secured to said framework extending inwardly and upwardly from said lower frame member to said upper frame member, said side wall comprising a substantially continuous piece of an expanded metal lath material; an outer layer of building blocks set against and completely surrounding said side wall; and mortar interlocking said building blocks to one another and to said wall, said mortar being keyed through the openings in said metal lath material and being smoothly troweled on the interior surface of said wall to completely conceal said wall and framework.
